UNITED STATES PATENT OFFICE

ERNEST W. FREUDENBERG, OF LARCHMONT, NEW YORK

DESIGN FOR AN EMBROIDERED LACE

Application filed March 5, 1931. Serial No. 38,953. Term of patent 3½ years.

To all whom it may concern:

Be it known that I, ERNEST W. FREUDENBERG, a citizen of the United States, residing in Larchmont, New York, county of Westchester, State of New York, have invented a new, original, and ornamental Design for Embroidered Lace, of which the following is a specification, reference being had to the accompanying drawing, forming part thereof:

The figure is a plan view of embroidered lace, showing my new design.

The drawing shows a repeat design and the dot and dash lines include one complete element.

I claim:

The ornamental design for embroidered lace substantially as shown and described.

ERNEST W. FREUDENBERG.
